BY *Victor J. Evans*

ATTORNEY

UNITED STATES PATENT OFFICE.

HARRISON B. SMITH, OF BAYSIDE, NEW YORK.

SEAL FOR RECEPTACLES.

1,288,246.

Specification of Letters Patent. Patented Dec. 17, 1918.

Application filed July 5, 1917. Serial No. 178,689.

To all whom it may concern:

Be it known that I, HARRISON B. SMITH, a citizen of the United States, residing at Bayside, in the county of Flushing and State 5 of New York, have invented new and useful Improvements in Seals for Receptacles, of which the following is a specification.

This invention relates to seals or closures for receptacles such as bottles, jars and the like. The object of the present invention is to provide a seal in the form of a cap, which is of simple, cheap and effective construction and adapted to be used repeatedly for hermetically closing the mouth of such receptacle, and also adapted to be readily applied and removed without the use of tools or other implements.

A further object of the invention is to produce a stopper or cap of the type referred to which by reason of its resiliency will readily accommodate itself to variations in the size of the necks of receptacles and which will obtain a secure frictional hold or retaining fit on the neck of the receptacle 25 such as will prevent the displacement of the cap except when properly manipulated in the manner hereinafter described.

With the above and other objects in view, the invention consists in the novel construction, combination and arrangement of parts, 30 herein fully described, illustrated and claimed.

In the accompanying drawings:—

Figure 1 is a side elevation of the neck 35 of a receptacle showing the improved seal or cap in its applied relation thereto.

Fig. 2 is a central vertical section through the same.

Fig. 3 is a view similar to Fig. 2 illustrating the mode of application and removal of the cap.

Fig. 4 is a perspective view of the improved cap detached.

Referring to the drawings, 1 designates 45 the mouth or neck portion of a bottle, jar or other receptacle provided with an external annular bead 2 immediately below the rim edge thereof for coöperation with a sheet metal closure cap 3. While a receptacle of this character is shown for the purpose of 50 illustrating the present invention, any other type of receptacle having a bead or projection of a suitable character may be employed.

The cap 3 is provided with a flange 4 of 55 less diameter than the beaded portion of the neck and which is sufficiently resilient to be

sprung into engagement with the bead. The cap as a whole may be made of any resilient sheet metal of any suitable gage or thickness, and is formed with an annular or circumferential seat 5 adapted to receive the bead 2 as clearly indicated in the drawings. In sealing the receptacle, the cap is primarily positioned at an angle to the mouth of the receptacle as shown in Fig. 3 so as to bring one side of the flange opposite the adjacent side of the bead with the annular seat or groove 5 in engagement with the bead, whereby the distance between such side of the flange and the diametrically opposite side of the bead will be decreased, permitting the cap to be sprung downwardly to the position shown in Figs. 1 and 2, over the bead to interlock with the latter and close the mouth of the receptacle. It will be observed that in this way the cap may be applied without the use of a tool and will be firmly and securely held in position against any possibility of casual displacement while at the same time the resiliency of the flange 80 will allow the cap to be readily removed without the use of a tool by tilting the cap at an angle while pressing the same off the neck of the receptacle.

The cap ordinarily contains a resilient 85 compressible disk 6 of such material as cork, rubber, paper, or felt, or any other material having a springy, yieldable or cushioning character. By the expansive action of said resilient disk, a firm frictional hold or grip 90 is obtained between the cap and the bead of the receptacle throughout the circumference of the bead.

The cap may be employed in conjunction with any suitable lining or sealing disk 6 of 95 any ordinary or suitable type for the purpose of hermetically closing the receptacle, but is preferably used in conjunction with the type of disk referred to and herein shown, thus providing for an absolutely air 100 and liquid tight closure of the neck of the receptacle. The elasticity of the cap readily adapts it to be applied and removed and to accommodate itself to necks and the beads thereof varying somewhat in size or having 105 irregularities in the surface thereof.

The flange 4 of the cap need extend only a sufficient distance below the annular seat 5 and the bead 2 to provide for reducing the diameter of the flange below said bead for 110 the purpose of obtaining a continuous or endless shoulder which binds against the

2

bottom of the bead and serves to frictionally retain the cap in place. This reduces the amount of material in the cap, enables thinner material to be used in the formation of the cap, reduces the cost of the cap, and renders the manufacture thereof easier and cheaper. It further adds to the ease of removing and replacing the cap and avoids the necessity of selecting any particular point around the cap upon which to exert force either in applying or removing the cap.

10 I claim:—

15 A cap for receptacles having an external bead or projection, said cap having a resilient circumferential flange of less normal diameter than the beaded portion of the receptacle and formed immediately above said flange with an annular uninterrupted out-

standing channel, said channel being adapted to receive the bead at any part of said channel to permit the cap to be placed at an angle upon the mouth of the receptacle, the cooperation of the bead and channel in such engagement reducing the distance between that portion of the flange underlying such engaged portion of the channel and the diametrically opposite side of the bead, to permit the cap to be sprung downward to cause the flange to engage beneath the bead throughout the full circumferential length of the bead and flange, and a compressible disk to be held in the cap and compressed against the mouth of the receptacle in the final seating of the cap.

20 25 30 35 In testimony whereof I affix my signature.

HARRISON B. SMITH.
